Atty.

UNITED STATES PATENT OFFICE.

FRANK PARIZEK, OF CHICAGO, ILLINOIS.

HINGE.

1,159,529.

Specification of Letters Patent.

Patented Nov. 9, 1915.

Application filed March 2, 1915. Serial No. 11,476.

To all whom it may concern:

Be it known that I, FRANK PARIZEK, a citizen of the United States, residing at Chicago, in the county of Cook and State of Illinois, have invented a certain new and useful Improvement in Hinges, of which the following is a full, clear, concise, and exact description, reference being had to the accompanying drawings, forming a part of this specification.

My invention relates to hinges and more particularly to such hinges as are used for instance in connection with windows or wind shields of automobiles. In hinges of this nature there are usually two relatively movable members having frictional engagement together with suitable stop or catch mechanism adapted to normally hold the members in any one of a plurality of resting positions.

My invention is designed more particularly to reduce the friction between the relatively movable members, thus to decrease the actual power necessary in shifting the device from one resting position to another, while at the same time retaining a great pressure between the two members so as to secure an efficient lock for the members in any one of their resting positions.

In the preferred form of my invention, I provide a ball bearing structure in connection with the two rotatable members so as to keep them separated, and then provide additional, preferably spherical, elements which control the holding of the members in any one of their predetermined resting positions.

I will explain one form which my invention may take more in detail by referring to the accompanying drawing in which—

Figure 1 shows a wind shield equipped with my improved hinge; Fig. 2 is a side view thereof, the window being in section; Fig. 3 is a transverse sectional view of my improved hinge; Fig. 4 is a sectional view on line *a—a* of Fig. 3; Fig. 5 is a side view of one of the relatively rotatable members; Fig. 6 is a side view of the other rotatable member, and Fig. 7 is a partial sectional view on line *b* of Fig. 4.

Referring to Fig. 1, I show a casing 1 having a window 2 which is adapted to be held in any given position through the agency of my improved hinge 3.

My improved device consists of two relatively rotatable members respectively the

member 4 and the member 5. These members, as clear, are fastened respectively to the window and the casing. The element 4 has a ball race and the element 5 has a ball race 7, which ball races are placed in juxtaposition and accommodate balls 8 all as is more clear from Fig. 3.

In Figs. 5 and 6 ridges 9 and 10 are shown on the opposite sides of which the ball races 6 and 7 are to be found. The balls of course keep the face plate portions 11 and 12 respectively of the elements 4 and 5 separated a slight distance so that the relative rotation between these two members 4 and 5 occurs through the interposition of the balls 8. The two face plate portions of the elements are placed in juxtaposition as shown in Fig. 3 and are held tightly together by a spring 13, which spring has its tension controlled by the screw 14 and the nut 20. The screw 14 has a preferably triangular head as shown so that it fits in the depressed portion 15 of a face plate 16, which face plate is arranged on the outside of the element 4 as readily apparent. The screw passes through the central openings 17 and 18 respectively of the elements 4 and 5 and also passes through a cap 19 seen more clearly in Fig. 3. The nut 20 has a cotter pin 21 passing through the same and the screw 14 so as to prevent dislocation of the nut. The member 5 has projecting pins 22, 22 which fit in recesses 23 provided in the cap 19. The spring 13 as is apparent is interposed between the face plate portion 12 of the member 5 and the cap 19. The cap 19 has a plurality of recesses 24, which recesses accommodate springs 25, which springs impinge against the balls 26. These balls 26 are carried within apertures 27 provided in the face plate portion 12 of the member 5. Protruding portions of these balls rest in recesses 28 provided in the face plate 11 of the member 4.

It will be noted that the recesses 28 are smaller in diameter than the diameter of the balls 26 so that the balls are pressed against the edges of these recesses by the springs 25. As the members 4 and 5 are relatively rotated about the screw 14, the balls 26 pass from one recess 28 to the succeeding recess 28 and the face plate portions of the members are kept in their proper positions by the spring 13, the balls 8 providing a suitable ball bearing between these two members 4 and 5 as they are being rotated. From this it will be readily seen that the spring 13

may be adjusted to a considerable pressure so that any wear between the members 4 and 5 is readily compensated for and taken up and there is provided at all times a solid 5 piece of apparatus. The springs 25 are of course of such strength as to maintain the members in any one of their predetermined resting positions in which the balls 26 find lodgment against the edges of the recesses 10 28. The tapered portion of the screw head 14 within the tapered aperture provided within the stem 16 also assists materially in keeping the parts alined and tightly together. It will be seen that the members 4 15 and 5 are readily made of punchings and thus lend themselves to a very moderate priced construction.

From what has been described the nature 20 of my invention will be readily clear to those skilled in the art, and it will also be clear that modifications within the scope of the appended claims can be readily made without departing from its spirit.

Having however thus described one form 25 which my invention may take, what I claim as new and desire to secure by Letters Patent is:

1. In a device of the character described 30 the combination with a pair of relatively rotatable members, means for pressing said members toward each other, a ball bearing interposed between said members, and spring controlled detents in combination with means to hold said members in any 35 one of a plurality of resting positions.

2. In a device of the character described 40 the combination with a pair of relatively rotatable members, means including a cap for pressing said members toward each other, a ball bearing interposed between said members, and spring controlled detents in combination with means to hold said members in any one of a plurality of resting positions.

45 3. In a device of the character described the combination with a pair of relatively rotatable members, means including a cap for pressing said members toward each other, a ball bearing interposed between said 50 members, spring controlled detents in com-

bination with means to hold said members in any one of a plurality of resting positions, and springs for controlling said detents abutting said cap.

4. In a device of the character described 55 the combination with a pair of relatively rotatable members, means for pressing said members toward each other, said means including a bevel headed screw, and one of said members having a beveled face to co-operate with the beveled head of said screw, a ball bearing interposed between said members, and spring controlled detents in combination with means to hold said members in any one of a plurality of resting positions. 60 65

5. In a device of the character described 70 the combination with a pair of relatively rotatable members, means including a cap for pressing said members toward each other, a ball bearing interposed between said members, spring controlled detents in combination with means to hold said members in any one of a plurality of resting positions, a spring for controlling said detents abutting said cap, and means for preventing relative 75 movement between said cap and one of said members.

6. In a device of the character described 80 the combination with a pair of relatively rotatable members, means including a cap for pressing said members toward each other, a circumferential ball bearing interposed between said members close to the axis of rotation of said members, spring controlled detents in combination with means to hold said 85 members in any one of a plurality of resting positions, a spring for controlling said detents abutting said cap and abutting one of said members substantially at said ball bearing, and means for preventing relative 90 movement between said cap and one of said members.

In witness whereof, I hereunto subscribe my name this 17th day of February, A. D., 1915.

FRANK PARIZEK.
